UNITED STATES PATENT OFFICE

2,556,500

TOOTHBRUSH

Jack C. Levine, New York, N. Y.

Application November 13, 1947, Serial No. 785,729

3 Claims. (Cl. 15—185)

1

The present invention relates to an improved tooth brush of an extensible and retractable type which, because of its relatively small size, when collapsed, is highly and satisfactorily adaptable for efficient use by travelers in that it may be carried in one's pocket, in a pocket book, or the like.

Needless to say, I am sufficiently conversant with the state of the art to which the invention relates to appreciate that tooth brushes have been constructed in foldable form with a view toward promoting factors of compactness and convenience and for pocket book and pocket use. What is more, I am aware that the prior art teaches it to be old to utilize a relatively short shank or handle portion carrying the bristle head, the same being hingedly or otherwise foldably connected with a casing or the like which often functions, when in use, as a part of the handle structure.

An object of the present invention is to structurally, functionally and otherwise improve upon kindred tooth brushes such as fall in the category under advisement, this being accomplished through the medium of a simple sheath in which the tooth brush proper is slidably mounted for projectible and retractable utility, said sheath being provided with a simple cover which encloses the sheath, and also the tooth brush, when the latter is not to be used.

More specifically, novelty is predicated upon a sheath which is channel-shaped in cross sectional form and which is open at one end and closed at the opposite end, the side flanges or walls serving to mount a slidable portion of the tooth brush, and tooth brush carrying adaptor ears or the like on the hinged and slidably mounted cover member.

Other objects and advantages will become more readily apparent from the following description and the accompanying illustrative drawing.

In the drawing:

Figure 1 is a perspective view of a folding tooth brush constructed in accordance with this invention and showing the same folded and concealed;

Figure 2 is a view showing the cover opened up and the brush partly projected, said view being based on Figure 1;

Figure 3 is a horizontal section on the plane of the line 3—3 of Figure 1, looking in the direction of the arrows;

Figure 4 is a transverse section on the line 4—4 of Figure 1, looking in the direction of the arrows; and,

Figure 5 is a fragmentary perspective view of the anchorable end of the tooth brush showing the removable assembling and hinge pin.

2

Referring now to the drawing by distinguishing reference characters a tooth brush, as a unitary device is denoted by the numeral 6 and comprises a relatively short handle or shank 7 with a bristle equipped head 8 at one end. At the opposite or inner end of the shank an integral attaching and sliding block 9 is provided and this has a bore 10 to accommodate an insertable and removable hinging and assembling pin 11.

10 The tooth brush 6 is adapted to slide and be retracted within the confines of the aforementioned sheath 12 and the latter is a substantially rectangular longitudinally elongated part whose major portion is channel-shaped in cross section and includes a bottom or web 13 and spaced parallel side walls or flanges 14 and 15 of duplicate construction. These flanges are provided with elongated slots 16 to accommodate end portions of the assembling and hinging pin 11. It will be noticed that the left hand end portion of the sheath is closed in that I provide a transverse end wall at 17 and a similar topping wall at 17a, the two completely enclosing this end of the sheath. Also the wall 17a coacts with the flanges 13 and 14 in defining a shoulder 18. The block 9 fits snugly and slides between the web 13 and flanges 14 and 15. The shank 7 has wiping or sliding contact with the interior of one of said flanges.

The brush and casing means includes, as before indicated, a cover unit or section 19 and this is adapted to cap over and enclose the otherwise open portions of the sheath. The side walls 20 are provided with finger niches 21 to facilitate opening and closing the cover. The end portions of the side walls 22 straddle the side flanges of the sheath and are hingedly attached to the extending end portions of the assembling pin 11. The short wall 23 closes the outer end of the cover and the top wall 24 substantially closes the top portion but terminates short at the point 25 and comprises a shoulder to coact with the shoulder 18. It follows that the portions 17 and 24 together provide effective closing means for the so-called top of the casing. Normally the cover is down over the sheath portion 12 and the brush is retracted into same in order that both parts 12 and 19 constitute an effective enclosing case for said brush. The brush is then protected against soilage and is in readiness for use whenever necessary or desired. The cover section may be lifted up and swung open to expose the brush. Then holding the cover section as a sort of an actuator, the two together coact with the brush and sheath enabling the brush to be projected beyond the open end of the sheath, this to the desired distance.

The pin 11 is insertable and bodily removable so that it is possible to disassamble all of the parts of the structure, also to replace the tooth-brush whenever it is unduly worn.

It is believed that by providing the brush handle with a block and slidably and snugly mounting same between the slotted side walls, the sheath coacts with the shank forming a suitable handle for operating the brush. The sheath however is effectively closable by the 10 cover means and all of the parts are therefore properly cooperable in providing a structure which attains the ends wanted.

A careful consideration of the foregoing description in conjunction with the invention as 15 illustrated in the drawing will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is 25 claimed as new is:

1. A pocket type tooth brush of the class described comprising a sheath embodying a web, spaced parallel side walls connected with and at right angles to said web, said side walls having elongated slots, said sheath being open at one end, closed at an opposite end and partly open along its top; said slots ranging from points just inwardly of said closed end to points spaced inwardly from said open end, a relatively small 35 projectible and retractable tooth brush embodying a shank having a head at its outer end and a block at its inner end, said block being slidably in said sheath and carrying an assembling and actuating pin, the end portions of the pin being slidable in the slots, and a cover for said sheath embodying sides hingedly connected with end portions of said pin, whereby said cover may be swung open and then slid relatively to the sheath for purposes of moving the tooth brush 45 in and out in relation to the sheath.

2. In a projectible and retractable tooth brush construction of the class described, a sheath, channel-shaped in cross section and open at one end, closed at an opposite end, and partially 50 open along its top, the side walls of said sheath having longitudinal oppositely disposed slots extending from said closed end to said open end, a relatively small tooth brush comprising a bristle head and a shank, said shank being provided at one end with an integral block, said block constituting a slide and being disposed between said side walls, a pin carried by said slide and slidably mounted in said slots, and a cover for said

sheath, said cover also being channel-shaped in cross section and including side walls and a web connecting the side walls with each other, said cover fitting over the sheath and being closed at its outer end, the latter serving to close the otherwise open outer end of said sheath, said cover also being closed along its top and having sides attached to the aforementioned pin.

3. In a projectible and retractable tooth brush construction of the class shown and described, an elongated sheath closed at one end and open at the opposite end, the top of the sheath being open for the greater part of its length but closed with a relatively short top wall at the aforementioned closed end of the sheath, said top wall providing a shoulder, the side walls of said sheath being provided with longitudinal slots, said slots extending from points inwardly of said closed end to points just inwardly of said open end, a substantially rectangular block slidably mounted in said channel between the side walls and bottom of the channel, a tooth brush having a shank portion attached at one end to said block, said shank portion being in sliding contact with the interior of one of the slotted walls, said shank being provided on its outer end with a bristle brush, the block and tooth brush being adapted to recede wholly within the confines of said sheath, and a cover also 20 channel-shaped in cross section including a web constituting a top for the otherwise open portion of the top of said sheath, having side walls enclosing the slotted side walls of the sheath and having a closed end closing the otherwise open end of the sheath, said web being adapted to abut the aforementioned shoulder, the side walls having extensions projecting beyond the corresponding end of the web, said extensions straddling the slotted walls of said sheath, and a pin piercing the extensions and block and passing through and beyond the respective slots.
